UNITED STATES PATENT OFFICE.

JOSEPH JAMES BRIGGS, OF BELFAST, IRELAND.

EMBROIDERY ATTACHMENT FOR SEWING-MACHINES.

1,262,441.

Specification of Letters Patent. Patented Apr. 9, 1918.

Application filed April 14, 1915. Serial No. 21,365.

To all whom it may concern:

Be it known that I, JOSEPH JAMES BRIGGS, a subject of the King of Great Britain and Ireland, residing at Belfast, Ireland, have 5 invented certain new and useful Improvements in and Relating to Embroidery Attachments for Sewing-Machines, of which the following is a specification.

This invention relates to so called duplicating attachments for use in connection with embroidery and like sewing machines and of the class by means of which a worker can simultaneously reproduce a number of repeats from a single pattern, and it has for 10 its object to provide improved devices of this class which permit of a practically universal movement of the work holder and whereby the movements of the work holder controlled by the operator are simultaneously and accurately repeated by the other work holders, thus producing the repeats as 15 required.

Under my invention I employ parallel link motions or equivalent to produce the required automatic repeating of right and left, and back and forward movements of the work holder controlled by the operator, which movements are, by said parallel link motions, communicated to the other work 20 holders. Turning movements of the work holder controlled by the operator are, or may be, simultaneously repeated at the other work holders by connecting each work holder with a turnable wheel at the end of a supporting bar or equivalent, the other end of 25 said bars or equivalent being pivotally connected to the parallel link motions which give right and left hand movements, while intermediate the two ends of each bar I provide another wheel or equivalent, and connect said last mentioned wheels by a parallel link motion or equivalent, so that the turning of one wheel will simultaneously and similarly turn the other wheels of the series, 30 while each of said wheels is pivotally connected at its center with the parallel link motion which produces back and forward movements, the movements of the first mentioned wheels connected with the work 35 holders are communicated to the last mentioned wheels by adjustable belts, or bands, or

chains, and for this purpose I find that in practice, bands of steel or of covered whalebone are very suitable and free from any backlash or stretching. The parallel link 55 motions or any of them may be arranged above or below the work bench as desired, or as may be found most convenient.

For the purpose of illustrating my invention I have shown on the annexed drawings 60 certain embodiments thereof, but it is to be understood that my invention is not limited to the exact arrangement and organization of parts as herein set forth.

Figure 1 is a front elevation of a duplicating apparatus in accordance with my invention.

Fig. 2 is a plan view thereof.

Fig. 3 is an enlarged front elevation of one unit of the apparatus.

Fig. 4 is a plan view of Fig. 3.

Fig. 5 is a side elevation looking in the direction of the arrow *a*, Fig. 3.

Fig. 6 is a side elevation and Fig. 7 is a plan view of a slightly modified form of the 75 apparatus.

On the drawings the same reference letters wherever repeated indicate the same or similar parts.

Referring to the drawings and the example of my invention shown at Figs. 1 to 5 inclusive, the hoops or the like *a* are each removably secured to a semicircular supporting bracket or holder *b* which is, or may be, hinged or otherwise secured at *b*¹ (see Figs. 80 85 3 to 5) on pins carried by a rotatable spindle *c* which is supported in the forked end *d*¹ of a lever *d*, the spindle *c* having secured thereto a wheel *c*¹ and the lever *d* which supports the spindle *c* and wheel *c*¹ is pivotally supported on a spindle *e* carried by the forked end *f*¹ of a lever *f* which is pivotally supported at its end *f*² on a spindle *g* supported in a bearing *g*¹ which may be fixed to the work bench or which may as in the example shown, be carried by a slideable bar *h*. The bar *h* would preferably, as shown in Fig. 5 be adapted to slide on rollers *h*¹ suitably supported.

The lever *d* which is pivotally supported 100 on the spindle *e* extends rearwardly, and at its end *d*² it pivotally supports a link or its

equivalent k which extends between and connects all the lever ends d of the apparatus. Secured to each spindle e is a lever or crank l having pivotally connected to its end l^1 a link or equivalent m which extends between and connects all the ends l^1 of the cranks l . Secured to each spindle g is a crank or lever o having pivotally secured at its end o^1 a link or equivalent n which extends between 10 and connects all the cranks o . Each spindle e in addition to having the crank l secured thereto has also a wheel e^1 secured to it and a band or belt p connects the wheel e^1 with the wheel e^1 so that any turning movement 15 of the wheel e^1 will produce a corresponding movement of the wheel e^1 and by means of the cranks l and link m all the wheels e^1 and e^1 will be correspondingly and simultaneously turned so that the turning of one hoop 20 a will correspondingly and simultaneously turn all the other hoops a . A transverse movement of one of the hoops a will cause the lever d connected therewith to move the lever f and its spindle g and correspondingly 25 move the crank o secured thereto and by means of the link n a corresponding and simultaneous movement of the other hoops a is obtained. Longitudinal movements of 30 one of the hoops a will move its corresponding lever d about its spindle e so that its end d^2 will correspondingly move the link k and so simultaneously give a corresponding longitudinal movement to the other hoops a of the apparatus. The cranks l and link m 35 and the cranks o and link n could be replaced by pulleys and suitable driving means such as shown in Figs. 6 and 7 and it may be found that such substitution would make for increased smoothness in the operating 40 of the apparatus.

The hoops a are shown in Fig. 3 as held in place in the semicircular bracket or holder b by means of suitable clips b^2 . Suitable bearings are provided for the spindles and other 45 moving parts. The sliding bar H may be operated in any suitable manner.

The hinging of the bracket or holder b is intended to permit of its being turned up from the work table when desired. The 50 band drive p is preferably provided with tension adjuster p^1 , and holes p^2 are preferably provided in the band p to engage corresponding projections on the wheel c^1 so as to insure a positive drive.

55 In the slightly modified form of the apparatus illustrated at Figs. 6 and 7, the sprocket wheel c^1 is turned when the work holder or hoop is turned, the hoop being attached to the sprocket wheel c^1 , and its turning movement is conveyed by the band A to pulley A^1 and from pulley A^1 by band A^2 to pulley A^3 and at the same time turning 60 pulley A^4 (the pulleys A^3 and A^4 being fast on a common spindle A^5) and from the pulley A^4 by bands A^6 and A^7 a corresponding 65

turning movement of the other hoops is obtained.

The arm d and pulley B are in one piece and any turning movement of the arm d turns the pulley B and by the band B^1 the 70 loose pulley B^2 is turned causing the bands B^3 to transmit the movement of the one arm d to the other arms d .

The arm C and pulley C^1 are in one piece and the turning of the arm C correspondingly turns the pulley C^1 with the result that the bands C^2 transmit the movements of the one arm C to all the other arms C . 75

Having now fully described my invention, what I claim and desire to secure by 80 Letters Patent is:—

1. A duplicating attachment for use in connection with sewing machines, comprising, in combination, a plurality of pivotally supported levers, a plurality of work holders pivotally carried by said levers, driving bands connecting said work holders to allow of rotary movements of one being repeated simultaneously by the others, and link mechanism connecting said levers to produce 85 similar longitudinal and transverse movements of said holders.

2. A duplicating attachment for use in connection with sewing machines, comprising, in combination, a slidably supported 90 bar, levers rotatably carried by said bar, a plurality of work holders pivotally carried by said levers, driving bands connecting said work holders to allow of rotary movements of one being repeated simultaneously by the 95 others, and link mechanism connecting said levers to produce similar longitudinal and transverse movements of said holders.

3. A duplicating attachment for use in connection with sewing machines, comprising, in combination, a set of levers pivotally supported at one end, a second set of levers, a set of spindles connecting each of said second set of levers with one of said first set of levers, wheels carried by said spindles, 100 a second set of spindles each mounted in one of said second set of levers, pins and wheels carried by said second set of spindles, brackets pivotally connected with said pins, 105 hoops, means adapted to secure said hoops to said brackets, bands connecting the wheels on the first set of spindles with those on the second set, and bands connecting the wheels on the first set of spindles with one another. 110

4. A duplicating attachment for use in connection with sewing machines, comprising, in combination, a slidably supported bar, a set of levers carried by said bar, a second set of levers, a set of spindles connecting each of said second set of levers with one of said first set of levers, wheels carried by said spindles, 115 a second set of spindles each mounted in one of said second set of levers, pins and wheels carried by said second set of spindles, 120

ond set of spindles, brackets pivotally connected with said pins, hoops, means adapted to secure said hoops to said brackets, bands connecting the wheels on the first set of 5 spindles with those on the second set, and bands connecting the wheels on the first set of spindles with one another.

In testimony whereof I affix my signature in presence of two witnesses.

JOSEPH JAMES BRIGGS.
